UNITED STATES PATENT OFFICE.

GEORGE H. PIERCE, OF QUINCY, MASSACHUSETTS, ASSIGNOR TO NEW ERA MACHINERY COMPANY, OF BOSTON, MASSACHUSETTS, A CORPORATION OF NEW JERSEY.

OFFSET-WEB-FEED MECHANISM FOR PRINTING-PRESSES.

No. 857,758.

Specification of Letters Patent.

Patented June 25, 1907.

Application filed February 12, 1906. Serial No. 300,620.

To all whom it may concern:

Be it known that I, GEORGE H. PIERCE, a citizen of the United States, residing at Quincy, in the county of Norfolk and State 5 of Massachusetts, have invented new and useful Improvements in Offset-Web-Fee Mechanism for Printing-Presses, of which the following is a specification.

This invention relates to an improved 10 mechanism for automatically feeding, at intervals, an offset web in a printing press across the face of the platen or impression plate in said printing press, the object of the invention being to present at intervals a new 15 surface of offset web against which the paper is pressed by the form during the printing operation.

This invention is particularly adapted to 20 be used in printing presses of the type in which a web of paper is fed intermittently through the machine and is printed upon at intervals by different forms carrying different sets of type and printing in different colored inks.

25 The invention consists in the combination and arrangement of parts set forth in the following specification and particularly pointed out in the claims thereof.

Referring to the drawings:—Figure 1 is a 30 side elevation of a portion of a printing press with my improved offset web feed mechanism illustrated in connection therewith. Fig. 2 is an end elevation of the same, as viewed from the left of Fig. 1. Fig. 3 is a 35 section partly in elevation taken on line 3—3 of Fig. 2 looking toward the left in said figure. Fig. 4 is an enlarged section, partly in elevation, taken on line 4—4 of Fig. 1 looking toward the left in said figure. Fig. 5 is an 40 enlarged detail side elevation, partly broken away, of the pawl and ratchet feed mechanism as viewed in the opposite direction to that in which Fig. 1 is viewed. Fig. 6 is a section taken on line 6—6 of Fig. 5 looking 45 toward the left in said figure. Fig. 7 is a section taken on line 7—7 of Fig. 5 looking toward the right in said figure. Fig. 8 is a section taken on line 8—8 of Fig. 4 looking toward the right in said figure and illustrating 50 in detail the intermittent gears.

Like numerals refer to like parts throughout the several views of the drawings:

In the drawings, 10 is the frame of the ma-

chine consisting of two side standards 11, 11' joined together by stay bolts and fastened to 55 and supported upon the main bed frame 12 of the machine. The platen 13 consists of a stationary plate rigidly fastened to the bed frame 12. The offset web 14 consists of a web of paper which extends across the lower face of 60 the platen 13 and is fastened at its opposite ends, respectively, to a supply roll 15 and a receiving roll 16. Said offset web extends from the supply roll (see Fig. 3) downwardly partially around a tension roll 17, against the periphery of which it is held by a flat spring 18, thence across the lower face of the platen 13, being guided at the opposite edges of said 65 platen across guide rolls or idlers 19, 19 journaled to rotate freely upon said platen. 70

From the platen 13, the web of paper constituting the offset web extends upwardly at an angle and partially around and in contact with a feed roll 20, being held firmly in contact with said feed roll by presser rolls 21. 75 Said presser rolls are fast to a shaft 21' journaled to rotate upon arms 22, 22 pivoted at 23 to the side standards 11, 11'. Said rolls 21' are pressed downwardly upon the periphery of the feed roll 20 by means of adjusting screws 24, 24 having screw-threaded engagement with ears 25, 25 formed upon the side standards 11, 11'. The offset web passes from between the feed roll 20 and 80 presser rolls 21 to the receiving roll 16 and 85 the end of said offset web is fastened to said receiving roll.

The main driving shaft 26 of my improved offset web feeding mechanism is rotated by a sprocket chain 27 and sprocket gear 28 fast to said shaft 26, the chain 27 being driven by 90 a sprocket gear fast to a rotary shaft upon the main frame of the machine (not shown in the drawings). Said main driving shaft 26 has another sprocket gear 29 fast thereto by 95 a frictional clamp 30 Fig. 3 and connected by a sprocket chain 31 to a sprocket gear 32 fast to a shaft 33 journaled to rotate in bearings provided in the frame and having fast to its right hand end (Fig. 3) a bevel gear 34 which 100 meshes into another bevel gear 35 fast to a shaft 36 to which the receiving roll 16 with its flanges 16' is fastened.

It will be seen that the rotation of the receiving roll 16 causes the offset web to be 105 wound upon the central drum of said roll as

it is paid off or fed thereto by the intermittent rotary motion of the feed roll 20. It is desirable in the device of this invention to feed the offset web intermittently across the 5 face of the platen at the end of a certain number of rotations of the main shaft, say five in number, so that a new surface of the offset web extends entirely across the under face of the platen and is presented to the face 10 of the paper to be printed beneath the platen 13. The offset web then remains stationary for four rotations of the main shaft 26 and is then fed during the next rotation of said shaft as hereinbefore described. To obtain 15 this intermittent motion of the offset web a pawl and ratchet mechanism is used in which a ratchet 38 is fastened to the shaft 37 and a pawl carrier 39 is journaled to rock freely upon said shaft 37. A pawl 40 is pivoted to 20 the pawl carrier 39 and engages the teeth of the ratchet 38; when the parts are in the position illustrated in Fig. 5. Said pawl is pivoted to said pawl carrier at 41 and is connected by a pin 42 to a lever 43 which, in 25 turn, is pivoted at 44, to the pawl carrier 39. It will be noted that the lever 43 and the pawl 40 lie side by side upon the rear face of the pawl carrier 39. Immediately above the 30 pawl 40 and the lever 43 is located one end of a rock shaft 45 provided with a finger 46 fast thereto and adapted, by the rocking of the shaft 45 and mechanism hereinafter described, to be moved alternately into alignment with the pawl 40 and with the lever 43.

35 Assuming the parts to be in the position illustrated in Figs. 5 and 6, it will be seen that the finger 46 is in alignment with the pawl 40, and when in this position said pawl is brought into contact with the teeth of the 40 ratchet 38. When said rock-shaft 45 and finger 46 are moved, however, to the position shown in dotted lines (Fig. 6) it will be seen that the finger 46 is in alignment with the lever 43, and in this position, when the lever 45 43 is rocked by the pawl carrier 39 until said lever comes in contact with the finger 46, said lever will be pushed downwardly by the finger 46 and through the pin 42 the pawl 40 will be lifted out of contact with the teeth of 50 the ratchet 38 until the spring pin 47, carried by the pawl carrier 39, is forced into the recess 48 formed in the pawl 40 (Fig. 7), said spring pin thus constituting a catch and holding said pawl out of contact with the 55 teeth of the ratchet until the rock-shaft 45 is actuated to rock the finger 46 into alignment with the pawl 40, when said pawl will be moved downwardly into contact with the teeth of the ratchet 38, said spring pin 47 being forced out of the recess 48 to allow of such movement.

The rock-shaft 45 is journaled to rock in bearings formed in brackets 49 fast to the side standard 11 and is rocked by an arm 50 60 fast thereto and moved upwardly by a spring

51, one end of which is fast to said arm the other to said standard 11, while a downward motion is imparted to said arm by a link 52 connecting said arm to a lever 53 pivoted at 54 to the side standard 11 and provided at 70 its right hand end (Fig. 1) with a friction roll 55 which rides upon the periphery of a cam 56, fast to an intermittent gear 57 (Figs. 1 and 4). Said cam 56 has two raised portions 56' 56'' thereon arranged diametrically 75 opposite each other, and in the position illustrated in Fig. 1, one of said raised portions 56' is in contact with the roll 55, so that the lever 53 is tipped upwardly at the right hand end thereof, the link 52 is pulled downwardly, 80 and the rock-shaft 45 rocked to bring the finger 46 into alignment with the pawl 40, as illustrated in Fig. 6. The intermittent gear 57 and cam 56 rotate as one piece upon a stud 58 fast to the standard 11 and are rotated 85 by an intermittent gear 59, said intermittent gear 57 having ten spaces 57' formed in its periphery and the intermittent gear 59 having one tooth 59' thereon, said intermittent gear 59 fast to a shaft 60 journaled to rotate 90 in bearings formed in the sides of the bed frame 12.

The shaft 60 has the tension roll 17 fast thereto and is rotated by a bevel gear 61 which meshes into a bevel gear 62 fast to the 95 shaft 26. A rocking motion is imparted to the disk-shaped pawl carrier 39 by a gear 63 which is fast to the pawl carrier 39 rocks as one piece therewith and meshes into a rack 64 constructed to slide in a bracket 65 journaled to rock loosely upon the shaft 37 and held against longitudinal movement upon said shaft by a collar 66 on one side thereof and by the gear 63 upon the opposite side thereof. The rack 64 is pivotally connected 100 to a wrist pin 67 formed upon a sliding nut 68 having screw-threaded engagement with an adjusting screw 69 and constructed to be moved in ways 70 by said screw longitudinally of a crank-arm 71 formed upon the 105 outer end of the shaft 60 (Figs. 1 and 4).

The paper 72, upon which the printing is to be done, passes between a form 73 containing the type and the platen 13. The form 73 is fast to a form carrier 74 pivoted at 75 to the 115 bed plate of the machine, a rocking motion being imparted to said form carrier 74 by a link 76 connected to suitable mechanism to impart a vertical reciprocatory motion thereto. The paper 72 is liable, in certain classes of 120 printing presses, to have freshly printed matter upon the upper as well as upon the lower face thereof, and to prevent said freshly printed matter upon the upper face of said paper from being smutched as it is fed against the 125 offset web in the operation of the machine reciprocatory guides 77, 77 and 78, 78 are provided, which, at the proper time in the operation of the machine, are respectively raised and lowered until the paper 72 is 130

brought into and out of contact with the lower face of the platen 13.

The guide 77, (Figs. 1, 3 and 4) consists of two blocks 79, 79 located upon opposite sides, respectively, of the sheet of paper 72 and joined together by rods 80 and 81. One of said rods 80 (Fig. 4) is provided with right and left screw-threads which have screw-threaded engagement with the blocks 79, 10 so that by rotating said rods 80 the blocks 79 are brought toward or away from each other according to the direction in which the rod 80 is rotated, thus regulating the guide blocks to the width of the paper which is to be fed 15 therebetween through the grooves 82 provided in said blocks beneath the rods 80 and 81. The opposite ends of the rod 80 are connected by spiral springs 83 to pins 84 fast to brackets 85 upon the bed frame 12, 20 said springs tending to hold the rods 80 and guide blocks 79 upwardly and thus to assist in holding the web 72 against the under face of the platen 13. Said guide blocks and rods are forced downwardly for the purpose of 25 removing said paper from the under face of said platen by slides 86 constructed to move vertically in ways formed in the brackets 85, and each provided at its upper end with a friction roll 87 arranged to bear against the 30 periphery of cams 88 fast to the shaft 60.

The guide 78 is similar in its construction and in its operation to the guide 77 and consists of two guide blocks 89, 89 connected together by a rod 90, said rod and guide blocks 35 being moved upwardly by spiral springs 91 and downwardly by slides 92 provided with friction rolls 93 which bear against the periphery of cams 94 fast to a shaft 95 journaled to rotate in the opposite sides of the bed 40 frame 12. The shaft 95 is rotated by a bevel gear 96 fast thereto and meshing into another bevel gear 97 fast to the shaft 26.

The receiving roll 16 and supply roll 15 are made interchangeable so that when the supply roll 15 becomes empty and the offset web becomes wound upon the receiving roll 16, said receiving roll may be removed from the side standards and placed in the position previously occupied by the supply roll, the 45 supply roll being placed in the position upon said standards previously occupied by the receiving roll, and thus the paper forming the offset web may be wound from one of said rolls to the other several times until it becomes unfit for use.

It will be seen and understood that by the arrangement of the supply roll and receiving roll, and the manner in which the paper is directed from one to the other, that the outer 50 face of the paper is alternately changed by the changing of the receiving roll to the position of the supply roll, that is, the outer face, against which the impression takes place, of the offset web, as illustrated in Fig. 3, be-

comes the inner face when the rolls 15 and 16 65 are interchanged.

The flanges 16' are made detachable from the center drum 16, so that when the roll 15 is substituted for the roll 16 as a receiving roll, as hereinbefore described, said flanges 70 are removed from the drum 16 and fastened to the drum of the roll 15.

The general operation of my improved offset web feed mechanism is as follows: Assuming the different parts of the mechanism 75 to be in the position illustrated in Figs. 1 and 3 of the drawings, the paper 72 is carried upwardly until it contacts with the offset web 14 by the springs 83 and 91, which operate, as hereinbefore described, to raise the guide 80 blocks 79 and 89 until the paper 72 contacts with the under side of said offset web 14. The form 73 is then brought upwardly by the rocking form carrier 74 until the face of the type contacts with the under face of the 85 paper 72. Said form is then lowered and the web of paper 72 is lowered to the position shown in Fig. 3 of the drawings, and said web of paper is then fed forward by appropriate mechanism (not shown in the drawings). 90 After five impressions have been made upon the paper 72, the offset web is fed forward in the direction of the arrow *a* (Fig. 3) and across the under face of the platen 13 until a new section of said offset web extends entirely across the face of said platen. This feed takes place during every fifth rotation of the shaft 26 and said offset web is fed by the pawl and ratchet mechanism hereinbefore described. At every fifth rotation of the 100 shaft 26 one of the raised portions 56' upon the cam 56 comes in contact with the roll 55 upon the lever 53 and tips said lever upon its pivot, thus rocking the rock-shaft 45 and moving the finger 46 from the position shown 105 in full lines (Fig. 6) to that shown in dotted lines therein, thus bringing the finger 46 into alignment with the lever 43, and as the pawl carrier 39 is carried forward in the direction of the arrow, Fig. 5, said finger contacts with 110 the lever 43 and pushes the same downwardly, rocking the pawl 40 upon its pivot 41 by means of the pin 42 connecting said lever 43 and pawl 40 and lifting the pawl out of contact with the teeth of the ratchet 38 until 115 the spring pin 47 drops into the recess 48 and holds said pawl out of contact with the teeth of the ratchet during the next four rotations of the shaft 26 and during said four rotations the ratchet 38 as well as the feed roll 37 remains stationary, and also the offset web 14, it being understood that by the pawl and ratchet mechanism hereinbefore described 120 the offset web is fed at the end of every five rotations of the shaft 26 across the under 125 face of the platen to present a new surface of offset web to the platen or paper 72.

It will be understood that a continual pull

is kept upon the offset web 14 after it leaves the feed roll 20 by the receiving roll 16, so that as said offset web is paid off by the feed roll 20, it is wound upon the central drum 5 of said receiving roll, but when said offset web is not being thus fed by the feed roll 20 the frictional clamp hub 30 upon the sprocket gear 29 slips upon the shaft 26 and thus while said receiving roll 16 maintains a continual pull upon the offset web, between said roll and the feed roll 20, the slipping of said frictional clamp hub upon the shaft 26 allows the receiving roll 16 to remain stationary, except at such times as the offset web is being fed by the feed roll 20, as hereinbefore described.

It will be understood that after each impression of the type upon the paper 72 has taken place, said paper is carried away from the lower face of the platen 13 by the guide blocks 79 and 89, actuated by the mechanism hereinbefore described, and is then carried forward in the direction of the arrow *b* (Fig. 3), and just previous to said impression taking place the paper is carried upwardly into contact with said platen.

Having thus described my invention, what I claim and desire by Letters Patent to secure is:

30 1. In a printing press, a stationary platen, a web of paper constituting an offset web extending across the face of said platen, two rolls to which the opposite ends, respectively, of said offset web are fastened, a main driving shaft, mechanism driven by said shaft to intermittently feed said offset web from one of said rolls to the other across the face of said platen, and mechanism operated by said main shaft adapted to disconnect and connect said last named mechanism from and to, respectively, said main shaft.

2. In a printing press, a stationary platen, a web of paper constituting an offset web extending across the face of said platen, two rolls to which the opposite ends respectively of said offset web are fastened, a feed roll contacting with said offset web between one of said rolls and said platen, a main driving shaft, mechanism driven by said shaft to impart a rotary motion to said feed roll, and mechanism adapted to disconnect and connect said last named mechanism from and to, respectively, said main shaft.

3. In a printing press, a stationary platen, a web of paper constituting an offset web extending across the face of said platen, two rolls to which the opposite ends, respectively, of said offset web are fastened, a feed roll contacting with said offset web between one of said rolls and said platen, a main driving shaft, mechanism driven by said shaft to impart a rotary motion to said feed roll, and mechanism adapted to disconnect said last named mechanism from said main shaft and

render inoperative said feed roll actuating mechanism.

4. In a printing press, a stationary platen, a web of paper constituting an offset web extending across the face of said platen, a supply roll and a receiving roll, to which rolls the opposite ends, respectively, of said offset web are fastened, a feed roll contacting with said offset web between one of said rolls and said platen, a main driving shaft, mechanism driven by said shaft to impart a rotary motion to said feed roll, mechanism adapted to disconnect and connect said last named mechanism from and to, respectively, said main shaft, and mechanism to impart a rotary motion to said receiving roll.

5. In a printing press, a stationary platen, a web of paper constituting an offset web extending across the face of said platen, a supply roll and a receiving roll, to which rolls the opposite ends, respectively, of said offset web are fastened, a feed roll contacting with said offset web between one of said rolls and said platen, a main driving shaft, mechanism driven by said shaft to impart a rotary motion to said feed roll, mechanism adapted to disconnect and connect said last named mechanism from and to, respectively, said main shaft, and frictionally driven mechanism adapted to impart an intermittent rotary motion to said receiving roll.

6. In a printing press, a stationary platen, a web of paper constituting an offset web extending across the face of said platen, two rolls to which the opposite ends, respectively, of said offset web are fastened, a feed roll contacting with said offset web between one of said rolls and said platen, a pawl, a ratchet fast to said feed roll, mechanism adapted to impart a rocking motion to said pawl and through said pawl to impart an intermittent rotary motion to said ratchet and feed roll, and mechanism to move said pawl out of connection with said ratchet during the entire extent of said rocking movement.

7. In a printing press, a stationary platen, a web of paper constituting an offset web extending across the face of said platen, two rolls to which the opposite ends, respectively, of said offset web are fastened, a feed roll contacting with said offset web between one of said rolls and said platen, a pawl, a ratchet fast to said feed roll, mechanism adapted to impart a rocking motion to said pawl and through said pawl to impart an intermittent rotary motion to said ratchet and feed roll, a rock-shaft, a projection upon said rock-shaft, and mechanism to rock said shaft and bring said projection alternately into and out of connection with said pawl, whereby said pawl is alternately moved into and out of engagement with said ratchet.

8. In a printing press, a stationary platen, a web of paper constituting an offset web ex-

tending across the face of said platen, two rolls to which the opposite ends, respectively, of said offset web are fastened, a feed roll contacting with said offset web between one of said rolls and said platen, a rotary shaft, a ratchet fast to said rotary shaft, a pawl carrier journaled to rock upon said shaft, a pawl pivoted to said carrier and adapted to engage said ratchet, a rock-shaft, a projection upon 5 said rock-shaft, and mechanism to rock said shaft and bring said projection alternately into and out of connection with said pawl, whereby said pawl is alternately moved into and out of engagement with said ratchet.

15 9. In a printing press, a stationary platen, a web of paper constituting an offset web extending across the face of said platen, two rolls to which the opposite ends, respectively, of said offset web are fastened, a feed roll contacting with said offset web between one of said rolls and said platen, a ratchet, a pawl carrier, a pawl pivoted to said carrier and adapted to engage said ratchet, mechanism to move said pawl out of engagement with 20 said ratchet, and a catch supported upon said carrier adapted to engage said pawl and hold the same out of engagement with said ratchet.

25 10. In a printing press, a stationary platen, a web of paper constituting an offset web extending across the face of said platen, two rolls to which the opposite ends, respectively, of said offset web are fastened, a feed roll contacting with said offset web between one of said rolls and said platen, a ratchet, a pawl carrier, a pawl pivoted to said carrier, a lever pivoted to said carrier and connected to said pawl, and a rocking finger adapted to alternately engage said pawl and lever and throw 30 said pawl into and out of engagement, respectively, with said ratchet.

35 11. In a printing press, a platen, a web of paper constituting an offset web extending across the face of said platen, a feed roll for 40 said offset web, a ratchet fast to said feed roll, a pawl carrier, a pawl pivoted to said carrier, a lever pivoted to said carrier and connected to said pawl, a rocking finger adapted to alternately engage said pawl and 45 lever and throw said pawl into and out of engagement, respectively, with said ratchet,

and means to lock said pawl out of engagement with said pawl carrier.

12. In a printing press, a platen, a web of paper extending across the face of said platen, 55 guide blocks located upon opposite sides, respectively, of said platen provided with grooves adapted to engage the opposite edges, respectively, of said web of paper, rods extending transversely across said web of paper 60 to which said guide blocks are fastened, and mechanism to move said rods transversely thereof, whereby said web of paper is moved laterally thereof toward and away from said platen. 65

13. In a printing press, a platen, a web of paper extending across the face of said platen, guide blocks located upon opposite sides, respectively, of said platen, provided with grooves adapted to engage the opposite edges, 70 respectively, of said web of paper, rods extending transversely across said web of paper, to which said guide blocks are fastened, slides to which said rods are fastened at opposite ends thereof, respectively, and mechanism to impart a reciprocatory motion to 75 said slides, whereby said web of paper is moved laterally thereof toward and away from said platen.

14. In a printing press a platen, a web of 80 paper extending across the face of said platen, guide blocks located upon opposite sides, respectively, of said platen, provided with grooves adapted to engage the opposite edges, respectively, of said web of paper, rods extending transversely across said web of paper, to which said guide blocks are fastened, slides to which said rods are fastened at opposite ends thereof, respectively, cams adapted to move said slides in one direction, and 85 springs to move said slides in the opposite direction to that in which they are moved by said cams, whereby said web of paper is moved laterally positively away from said platen and toward said platen with a yielding pressure. 90 95

In testimony whereof I have hereunto set my hand in presence of two subscribing witnesses.

GEORGE H. PIERCE.
